UNITED STATES PATENT OFFICE.

RALPH R. WILLIAMS, OF DETROIT, AND JAMES T. MALLOY, OF RICHMOND, MICHIGAN,
ASSIGNORS TO THE WILLIAMS RADIO COMPANY, OF DETROIT, MICHIGAN, A COR-
PORATION OF MICHIGAN.

HORN.

Application filed October 25, 1922. Serial No. 596,914.

To all whom it may concern:

Be it known that we, RALPH R. WILLIAMS and JAMES T. MALLOY, citizens of the United States, residing at Detroit and Richmond, respectively, in the counties of Wayne and Macomb and State of Michigan, have invented certain new and useful Improvements in Horns, of which the following is a specification.

10 This invention relates to horns and more particularly to such devices especially adapted for reproduction of sound transmission in radio telephones while not limited to such use.

15 From each side of the reproducer diaphragms of telephone and radio receivers and phonographs there are sent forth wave trains of equal phase and amplitude. It is the present practice to utilize but one of these wave trains, the other being wholly lost, and in the case of radio and telephone receivers, the second train generally is held captive by the receiver casing and reflected back against the diaphragm setting up counter-vibrations therein which strongly affect the purity and clarity of the utilized train of sound waves.

It is an important object of the present invention to eliminate the usual harshness, indistinctness and blatancy so common to the usual methods of reproduction, by blending both sound wave trains emanating from a diaphragm in such a manner that perfect synchronism is obtained accompanied by purity of tone, accuracy of reproduction and a high degree of amplification unhampered by the counter vibrations above referred to.

As is well known sound waves vibrate substance, and in the usual construction of amplifying horns the sound waves set up independent vibrations in the material of the amplifiers which affect the purity of tone of the reproduced sound. We have found that in the practice of the present invention the method of utilizing both the trains of sound waves emanating from a diaphragm lends itself particularly well to the use of a construction employing a sonorous metal of substantial weight, the sound reflecting surfaces of which are highly polished.

In the drawings we have shown one embodiment of the invention. In this showing,

Figure 1 is a perspective view of a horn embodying the invention,

55 Figure 2 is a central vertical longitudinal sectional view, and,

Figure 3 is a section on line 3-3 of Figure 2.

In carrying out the invention we provide a suitable supporting base 5, which is preferably relatively narrow at its upper portion, as shown at 6 in Figure 2. A substantially spherical sound reflecting chamber 7 is mounted at the upper end of the base, the latter extending forwardly of the spherical portion as shown in Figures 1 and 2. The chamber 7 is provided forwardly with an annular shoulder 8 against which may be mounted a receiver 9. The receiver employed is preferably of a type wherein a portion of the rear wall may be removed to provide an opening 10 which communicates directly with the diaphragm 11 whereby the sound waves emanating from the rear of the diaphragm can pass without obstruction through the rear of the receiver casing. The rear portion of the chamber 7 may be formed of a cover plate 12, the inside surface of which forms a continuation of the inner 80 surface of the chamber 7. The cover 12 may be secured in place by any suitable means (not shown) and is provided with a central opening 13 through which the lead wires to the receiver may pass.

85 An amplifying horn 14 is mounted upon the base with its axis preferably in alignment with the center of the chamber 7 as shown in Figure 2. The vertex end of the horn 14 communicates through an opening 15 with the chamber 7.

A reverberatory sinus 16 affords communication between the amplifying horn and the chamber 7. As shown the sinus 16 has a forward opening 17 which communicates with the interior of the horn at a point adjacent the opening 15 while the rearward portion of the sinus communicates with the chamber 7 to the rear of the receiver 9 and its diaphragm. The front and rear lower walls 18 and 19 of its sinus 16 are preferably straight longitudinally, but curved transversely as shown in Figure 3 the wall 19 forming a smooth continuation of the spherical inner surface of the 100 chamber 7 and cover 12. In the preferred

construction the inner walls of the upper end of the base form the side walls of the sinus 16, but the invention is not limited to such a construction, it being thoroughly practicable to form a base separately instead of integrally as shown.

As stated, we prefer to employ a structure formed of sonorous metal of substantial weight and the inner surfaces of the horn 10 14, chamber 7, cover 12 and the walls of the reverberatory sinus 16 are preferably highly polished so as to present a minimum of resistance to the passage of the sound waves.

The operation of the device is as follows:

15 Transmitted sounds, reproduced by the diaphragm 11 emanate from both sides thereof, the forward train passing directly into the bell-shaped horn where they are amplified in the usual manner except that 20 the disclosed construction embodying the mirror-like inner surface of the horn tends to preserve the purity of tone. The wave train emanating from the rearward side of the diaphragm is reflected by the polished 25 surfaces of the chamber 7 and cover 12, without distortion, into the sinus 16, the walls of which in turn reflect the sound through the opening 17 where they are joined with the forward train of sound 30 waves. With the present construction it has been found that each wave train has the effect of modulating the other while the vibrations of one train reinforce the vibrations of the other in such a manner as to 35 produce an amplified reproduction of the transmitted sound wherein the true tonic qualities thereof are preserved, and not an amplification from the standpoint of mere loudness as is true of devices now in use. So 40 amplified, the reproduced sound has been found to possess remarkable purity and a carrying power not heretofore produced due to the absence of destructive counter-vibrations.

45 It is to be understood that the form of our invention herewith shown and described is to be taken as a preferred example of the same, and that various changes in the shape, size, and arrangement of parts may be 50 sorted to without departing from the spirit of the invention or the scope of the subjoined claims.

Having described our invention, we claim:

55 1. A device of the character described comprising a reflecting chamber adapted to receive a sound producing diaphragm, an amplifying horn having an inlet opening in its vertex end communicating with said chamber, and a reverberatory sinus communicating between said chamber and said horn.

2. A device of the character described

comprising a reflecting chamber adapted to receive a sound producing diaphragm, an amplifying horn having an inlet opening 60 in its vertex end communicating with said chamber, and a reverberatory sinus communicating between said chamber and said horn adjacent the inlet opening therein.

3. A device of the character described 65 comprising a reflecting chamber adapted to receive a sound producing diaphragm in its forward portion, an amplifying horn having an inlet opening in its vertex end communicating with the forward portion 70 of said chamber, and a reverberatory sinus communicating between the said chamber and said horn adjacent the inlet end thereof.

4. A device of the character described 75 comprising a substantially spherical reflecting chamber adapted to receive a sound producing diaphragm in its forward portion, an amplifying horn having its axis in alinement with the center of said chamber and having an inlet opening in its vertex 80 end communicating with the forward portion of said chamber, and a reverberatory sinus communicating between the said chamber and said horn adjacent the inlet end thereof.

5. A device of the character described 85 comprising a substantially spherical reflecting chamber adapted to receive a sound producing diaphragm in its forward portion, an amplifying horn having its axis 90 in alinement with the center of said chamber and having an inlet opening in its vertex end communicating with the forward portion of said chamber, and a reverberatory sinus communicating between the said chamber and said horn adjacent the inlet end thereof, the forward and rear lower walls of said sinus being substantially straight and inclined upwardly 95 toward their ends.

6. A device of the character described 100 comprising a relatively large reflecting chamber having a relatively small opening in one wall thereof, said chamber being adapted to receive a sound producing diaphragm adjacent said opening, an amplifier having its inlet end communicating 105 with said opening, and a reverberatory sinus of substantially greater area than said opening communicating between said chamber and said amplifier.

In testimony whereof we affix our signatures in the presence of two witnesses.

RALPH R. WILLIAMS.
JAMES T. MALLOY.
